TYPE-WRITING MACHINE.

945,035.

Specification of Letters Patent.

Patented Jan. 4, 1910.

Application filed August 27, 1908. Serial No. 450,487.

To all whom it may concern:

Be it known that I, EDWARD A. GOODHUE, citizen of the United States, and resident of Syracuse, in the county of Onondaga and 5 State of New York, have invented certain new and useful Improvements in Type-Writing Machines, of which the following is a specification.

My invention relates to typewriting machines and particularly to the ribbon mechanism of such machines.

The principal object of the invention is to produce a ribbon spool of simple construction with means for conveniently attaching the ribbon thereto, and devices co-operating with such spool which will allow the spool to be readily removed from and replaced in working position in the machine.

To the above and other ends my invention 20 consists of certain features of construction and combinations and arrangements of parts all of which will be fully set forth herein and particularly pointed out in the claims.

In the accompanying drawings, Figure 1 25 is a back view of a typewriter containing the present invention, parts being omitted and parts broken away and shown in section. Fig. 2 is a fore-and-aft vertical section of part of the mechanism. Fig. 3 is a fragmentary view similar to Fig. 1 but showing the spool holder retracted and a spool removed, and showing some of the other parts in section and in different positions from those shown in Fig. 1. Figs. 4, 5 and 6 are 35 a face view, an edge view and a sectional view, respectively, of the ribbon spool. Fig. 7 is a face view of one of the flanges of said spool. Fig. 8 is an isometric view of a drum and ribbon holding spring clamp. Fig. 9 is a face view of the other flange of 40 the spool. Fig. 10 is an enlarged view of the ribbon spool with one of the flanges removed and illustrating the manner in which the ribbon is secured to the drum.

45 My invention is applicable to typewriting machines generally but I have here shown it applied to a front-strike typewriter of the general sort shown in the application of Alexander T. Brown filed March 12, 1906, 50 Serial No. 305,561. The main frame of this machine comprises side plates 1 connected together at the rear by a back plate 2, said side plates being prolonged upward to form corner posts which support the top plate 3.

A paper carriage is mounted above said top 55 plate and is adapted to be fed across the same in a usual or suitable manner. Said carriage is propelled by a spring drum and certain gears which are mounted in a frame work 4 that depends from the top plate 3. 60 The mechanism mounted in said frame 4 comprises a transverse horizontal shaft 5 and means whereby when the carriage is moving toward the left said shaft is turned toward the rear of the machine. As best 65 shown in Fig. 3 this shaft has on its inner end a collar or hub 6 which forms a support for a ribbon spool 7. The outer end of the collar is enlarged as shown to prevent the spool from moving toward the left in 70 Fig. 3, and motion of said spool in the opposite direction is prevented by a collar 8. The spool is, however, free to turn on its support 6 except when said spool is connected with said support and the shaft 5 by 75 a driving device presently to be described. A second ribbon spool 10 is arranged coaxially with the spool 7, said spool 10 being journaled on a spring-pressed puppet or plunger 11 which is mounted in a bracket 12 80 depending from the top plate 3. As shown in Fig. 3 the bearing 11 consists of a collar mounted on the reduced end of a rod 13 where it is secured by riveting up the inner end of the rod. The bearing 11 and the 85 rod 13 are mounted in a counter-bored hole 14 in the bracket 12, and a spring 15, compressed between the part 11 and the bottom of the counter-bore, presses the bearing 11 toward the end of the shaft 5. As shown 90 in Fig. 3 the end of the hub 6 is formed with a shallow depression 16 which the end of the bearing 11 enters. The spool 10 when in position in the machine is held against motion axially by the hub 6 on the one hand 95 and on the other by a shoulder 17 on the bearing 11. The motion of the puppet under the impulse of the spring 15, is limited by the hub of a nut 18 which is threaded onto the end of the rod 13 and 100 which contacts with the bracket 12, thus preventing the pressure due to the spring 15 from coming on the shaft 5 and causing unnecessary friction.

When the two spools are mounted in the 105 machine as shown in Fig. 1 they are arranged coaxially side by side. The ribbon is led from one spool over suitable guides to

a ribbon vibrator at the front of the platen and back over similar guides to the other spool. These guides and the vibrator may be similar to those shown in the application of Alexander T. Brown above referred to.

- 5 In order to turn one or the other of the spools said spools have their adjacent flanges formed with ratchet teeth 20, Fig. 10, and said ratchet teeth are adapted to be engaged 10 by a feed dog 21 which as here shown consists of a plate of metal mounted in a slot cut in the end of the shaft 5 and the collar 6. This dog 21 is in effect a lever of the first order, being pivoted on a pin 22 passing 15 through the shaft 5 and through the lever. The construction is such that if the lever is rocked one way to the position shown in Fig. 3 it engages the ratchet teeth 20 on the spools 7 and if it is rocked the other way on 20 the pivot 22 it will engage the ratchet teeth on the spool 10; and the spool that is engaged by the dog will be driven positively with the shaft 5 to wind the ribbon thereon, and the other spool will be free to turn. In order 25 to retain the dog in either of these two positions said dog is formed on the end opposite its engaging end with a stud on which is journaled a grooved roller 23, and a pointed spring 24 has its pointed end in the groove 30 of the roller and the tension of the spring is exerted toward the roller. The construction is such that when the dog is in either of its two positions the spring holds it in that position and when the dog is snapped to 35 the other position the center of the roller passes the point of the spring and said spring presses the dog into its new position and retains it there. The point of the spring extending in the groove of the roller 40 prevents the roller from coming off of the stud on which it is journaled. In order to provide for shifting the dog by hand, a wire 26 is laid in a groove in the shaft 5 and the end of this wire is bent up as shown at 27 45 into a notch 28 in the dog 21. The construction is such that if this wire be moved endwise it will shift the dog about its pivot. The wire may be controlled in any suitable manner but as here shown its free end 29, 50 Fig. 1, is bent out through a collar 30 which is loosely mounted on the outer end of the shaft 5. By sliding this collar in or out the dog may be shifted from one spool to the other.
- 55 The construction of the ribbon spools is shown in detail in Figs. 4 to 10 inclusive. Each of these spools comprises a plain flange 32 and a toothed flange 33 and each of these flanges is preferably slightly dished at its 60 edge as shown at 34. These flanges are stamped out of sheet metal and the dishing referred to serves to guide the ribbon more readily into the spools. The ratchet teeth 20 in the flange 33 are formed by stamping 65 out parts of the metal as will be clearly un-

derstood from the drawing. The metal is cut through on three sides of a rectangle and bent on the fourth side.

The drum 35 of the spool consists of a strip of sheet metal bent into cylindrical 70 form but the ends not quite coming together, thus leaving a slot 36 in the spool. The drum has ears 37 projecting therefrom through holes 38 in the flanges 32 and 33 and these ears are riveted up, thus securing 75 the three parts of the spool together. The clamp for securing the ribbon in place consists of a spring 40 of flat metal bent into cylindrical form and inserted loosely into the hub or drum 35. One end of this spring 80 is bent off abruptly as shown in Fig. 10 at 41 and the other end is bent off obliquely as shown at 42, the edge of the oblique part 42 being pressed by the tension of the spring against the face of the abrupt part 41. The 85 slit in this spring comes opposite the slot 36 in the drum. The spring is secured in this position by means of lugs 43 which project into openings 44 in the flanges 32 and 33, each of said openings as shown in the present instance consisting of a branch of one of the holes 38. The drum 35 serves as a cover or housing for the clamp 40. The manner of securing the ribbon to this spool is illustrated in Fig. 10. The end of the ribbon 45 90 is folded back and any thin tool 46 may be used to insert the fold of the ribbon into the slot 36 and to force it between the parts 41 and 42 of the spring 40, thus forcing the two ends of the spring apart. When the 100 tool is withdrawn the edge of the part 42 is pressed by spring pressure against the face of the part 41, thus clamping the ribbon in place with sufficient force to retain it there for the purpose of feeding the ribbon. The 105 ribbon can, however, be detached at any time by pulling forcibly on it and forcing it out of the clamp. It will be seen that this ribbon spool is extremely simple in construction, the whole consisting merely of four 110 pieces of sheet metal. It will also be seen that the means for attaching the ribbon to the spool is very convenient as the end of the ribbon can be fastened in place, practically instantaneously. It will also be seen that it is very convenient to change the ribbon on the machine. In order to do this the 115 entire ribbon is wound on to the spool 10 and its end detached from the spool 7. The spool 10 can then be removed instantly by 120 simply withdrawing the plunger bearing by taking hold of the nut 18 which is formed with a milled head for the purpose, and a new spool can be instantly inserted. The new ribbon will then be threaded through the machine and its free end secured to the spool 7.

125 It will be noted that the spool 7 remains in the machine and that the spool 10 is detachable. These spools are so inexpensive 130

that it is practicable to sell the ribbon on the spool and the operation of putting the new ribbon into the machine is thus greatly simplified as the ribbon when purchased is 5 already on the spool and the spool can be inserted instantly into the machine. Where the operator has several different kinds of ribbons each ribbon can be on its own spool and any one of them can be put into the 10 machine at any time.

In order to provide for an automatic reversal of the ribbon feed when one of the spools is nearly exhausted certain cam devices are provided which are mounted on a 15 frame consisting of a piece of sheet metal 50 which is secured by rivets 51 to the frame 4 in front of and below the center of the ribbon spools. The frame 50 extends across both spools and has ears 52 bent up there- 20 form in which ears there is mounted a pivot rod 53. A small yoke-frame 54 is mounted on said rod 53 opposite the ribbon spool 10 and said yoke-frame comprises a flat arm 55 which is adapted to be pressed upward 25 against the ribbon that is on the spool 10, the arm at this time lying between the flanges of the spool. The yoke-frame is turned to press this arm upward in the manner indicated by means of a spring 56 coiled 30 about the rod 53 and connected at one end to the yoke-frame 54 and at the other end to the frame 50. The yoke-frame 54 also has an arm 57 situated between the spools 7 and 10 and having at its free end a triangular 35 piece 58 bent off therefrom, the inclined edge of this triangular piece being directed toward the rear of the machine and constituting a cam. When the ribbon is so far exhausted from the spool 10 that this cam is 40 raised into the path of the roller 23 said roller engages the cam which forces the roller away from the spool 10 and forces the opposite end of the dog 21 toward the spool 10 and into engagement with the ratchet 45 teeth 20 on said spool. A similar yoke-frame 60 is similarly mounted on the rod 53 opposite the spool 7 and is controlled by a spring 61 similar to the spring 56. This yoke-frame comprises a follower plate 62 50 which is adapted to be pressed by the spring 61 against the ribbon on the spool 7. The yoke frame 60 also has an arm 63 terminat- 55 ing in a cam 64 similar to the cam 58 but oppositely directed so that when the cam 64 comes into the path of the roller 23 it will shift the dog 21 into engagement with the spool 7. It will be noted that the arm 63 is made a little longer than the arm 57 so as to 60 avoid interference between the two cams 58 and 64.

The follower arm 55 is prolonged as shown in Fig. 2 toward the rear of the machine so that this cam can be more conveniently taken hold of by the hand of the 65 operator. This prolongation also prevents

the follower from getting in front of the spool shaft when the removable spool is inserted. When the spool 10 is being removed from or inserted in the machine the arm 55 is depressed beyond any position that it 70 would ever be moved to by the ribbon when the spool is in position. When the spool is being removed from the machine it is, of course, essential that it be entirely unwound from the spool 7. In order to prevent the 75 cam 64 from throwing the dog into engagement with the spool 7 at this time and thus possibly preventing the complete unwinding of the ribbon from that spool, I have provided the arm 57 with a bracket 65 which as 80 best shown in Fig. 3 extends over the arm 63 of the other yoke-frame. The position of this arm 63 is such that when both spools are in the machine said arm or bracket does not interfere with the movement of the arm 85 63 nor with the operation of any of the other parts; but when the arms 55 and 57 are depressed to a greater extent by the removal of the spool 10 then this bracket 65 moves to a position sufficiently low to prevent the arm 90 63 and cam 64 from rising high enough to engage the roller 23. By this device the dog 21 is prevented from being thrown into engagement with the spool 7 when the spool 10 is removed and the operator is free to 95 draw the ribbon entirely off from said spool 7.

Various changes may be made without departing from the spirit and scope of my invention.

What I claim as new and desire to secure by Letters Patent, is:—

1. A ribbon spool for typewriting machines, comprising a hollow drum or hub having a slot therein, and a clamp for the 105 ribbon mounted within said hollow drum, said clamp having a pair of jaws spring-pressed together and situated just within said slot, so that the ribbon can be pushed through said slot and between said jaws. 110

2. A ribbon spool for typewriting machines comprising a hollow drum or hub having a slot therein and a clamp for the ribbon mounted within said drum and operative independently of said drum to clamp 115 the ribbon.

3. A ribbon spool for typewriting machines comprising two flanges, and a drum formed of a strip of cylindrical form and having a slot left between the ends of the 120 strip; and a clamp for the ribbon mounted within said drum, said clamp consisting of a spring having a cylindrical form and having its two ends pressed together by its resiliency and adapted to receive the ribbon 125 between said two ends.

4. In a typewriting machine, the combination with a ribbon spool having a drum with a slot therein, of a clamp mounted within said drum for securing the end of 130

the ribbon to the spool, said clamp consisting of a spring having a cylindrical form and having its two ends pressed together by its resiliency and adapted to receive the ribbon between said two ends, and having lugs projecting therefrom into openings in the flanges of the spool.

5. In a typewriting machine, the combination with a ribbon spool, of a clamp 10 mounted on said spool for securing the end of the ribbon to the spool, said clamp consisting of a spring having a cylindrical form and having its two ends bent inward so as to form an angle with each other and 15 pressed together by its resiliency and adapted to receive the ribbon between said two ends.

6. In a typewriting machine, the combination of a support, a ribbon spool mounted 20 on said support and comprising flanges and a drum, and a clamp for the end of the ribbon comprising a spring mounted within 25 said drum and surrounding said support and operative independently of said drum to clamp the ribbon.

7. In a typewriting machine, the combination of a ribbon spool, a spring-pressed puppet or plunger on which said spool is mounted and means for withdrawing said puppet 30 or plunger from the spool to remove said spool from the machine.

8. In a typewriting machine, the combination of two ribbon spools arranged side by side, a support for one of said spools, a 35 puppet or plunger for supporting the other spool and means for withdrawing said puppet or plunger to remove the spool thereon from the machine.

9. In a typewriting machine, the combination of two ribbon spools arranged side 40 by side, a driving shaft passing through

one of said spools, a puppet or plunger for supporting the other spool, and means for withdrawing said puppet or plunger to remove the spool thereon from the machine. 45

10. In a typewriting machine, the combination of two ribbon spools arranged side by side, two supports for said spools, means for withdrawing one of said supports endwise to remove one of the spools from the 50 machine, and means for preventing said support from being withdrawn entirely from the machine.

11. In a typewriting machine, the combination of two ribbon spools, means for rotating one or the other of said spools to feed 55 the ribbon, means for automatically reversing the direction of ribbon feed, and means for preventing the operation of said automatic reversing means when it is desired to 60 unwind the ribbon completely from one of the spools.

12. In a typewriting machine, the combination of two ribbon spools, driving means for said spools, an automatic reversing device for said driving means comprising two 65 followers spring pressed against the ribbon on the spools, and means whereby one of said followers when moved to an abnormal position prevents the operation of the 70 other.

13. In a ribbon spool, the combination of a clamp for connecting a ribbon to the spool, and a cover or housing for the clamp, said 75 clamp being independent of said housing.

Signed at Syracuse, in the county of Onondaga and State of New York, this 21st day of August A. D. 1908.

EDWARD A. GOODHUE.
